UNITED STATES PATENT OFFICE.

ELIZABETH T. HINCKS, OF ANDOVER, MASSACHUSETTS.

PYROTECHNIC NOVELTY.

1,099,548.

Specification of Letters Patent.

Patented June 9, 1914.

Application filed December 10, 1913. Serial No. 805,846.

To all whom it may concern:

Be it known that I, ELIZABETH T. HINCKS, a citizen of the United States, residing at Andover, in the county of Essex and State of Massachusetts, have invented an Improvement in Pyrotechnic Novelties, of which the following is a specification.

The invention relates generally to a pyrotechnic novelty, and more particularly to an article constructed to exteriorly resemble a log and interiorly provided with combustible materials which, while burning will present a varied pyrotechnic effect.

The invention is designed to provide an article resembling a Yule-log, which is particularly serviceable as a Christmas novelty, in that it may be utilized at such period as emblematic of the Yule-log burning custom, with the added effect of practically any desired variation of pyrotechnic display incident to chemical treatment of part or parts of the article.

The invention in the preferred details of construction will be described in the following specification, reference being had particularly to the accompanying drawing, in which:—

Figure 1, is a plan view of a pyrotechnic device embodying this invention. Fig. 2, is an end elevation of the same. Fig. 3, is a longitudinal vertical section of the same. Fig. 4, is a transverse vertical section, taken on the dotted line 4—4, Fig. 3. Figs. 5, 6 and 7, are enlarged sectional views of some of the materials contained in the device to be referred to. Figs. 8 to 14 are views showing modified forms of cases which may be employed.

In the details illustrated in the drawing, which are designed as showing a simple type of the article the structure embodies a cylindrical casing 1, preferably of paper, or of some readily combustible material, which may, and preferably is, embossed or printed to simulate bark or the exterior of a log. The ends of the casing are maintained in desired open formation by annular members or rings 2, also of readily combustible material, and cylindrical ends 3 are secured in place in any appropriate manner to prevent the escape of the material from the casing. The cylinder ends are formed to permit a free air supply to the interior of the casing to permit ready combustion, and I contemplate for such ends any desired foraminous combustible material, cheese cloth, or mos-

quito netting having been found serviceable.

The interior of the casing is provided with a filling of such material or materials as are readily combustible, such material being selected as will inherently present or may be chemically treated to give the desired pyrotechnic effect in the burning of the log. In the present instance, I have shown such materials to include a quantity of cork particles 4, arranged adjacent the ends of the casing, small wood strips 5 arranged approximately centrally of the casing, and wood fiber 6 filling the remainder of the casing. Any or all of these materials may be chemically treated to produce a desired pyrotechnic effect, as for example one of the rings 2, with or without other adjacent part or parts of the material or materials may be treated with strontium chlorid, to produce a red flame in burning, while the other ring 2, and other adjacent part or parts of the material or materials may be treated with copper chlorid to produce a blue flame.

All, or practically all of the various parts of the novelty will be impregnated with paraffin, so that in combustion the burning will be prolonged; and the end rings 2 are purposely made quite thick, and when impregnated with paraffin will burn for a long period of time. I also contemplate the addition of any desired quantity or quantities, of incense, sandal wood, or the like, arranged in any position within the casing, so that during combustion the pleasing odors and effect of such material in burning will be given off.

The paper strip forming the casing proper has its edges overlapped longitudinally of the casing, and such edges are secured together only adjacent the rings 2, thereby providing an additional opening for air admission, and the casing wall may be further perforated at any desired point or points to increase the air supply.

At any appropriate point in the casing, preferably in the opening between the meeting edges of the casing wall I arrange a wick-like member or fuse 7, such member being preferably a section or wad of cotton fiber impregnated with paraffin or the like. The fuse within the casing is properly embedded in the materials therein, and beyond the casing is arranged in juxtaposition to a lighter 8, which latter is preferably a device known as a sparkler, designed, on igni-

tion, to burn with an unusual volume of sparks. The material of the lighter or igniting-device, is arranged on a wire 9, bent V-shaped, one limb of which extends along the side of the casing, preferably from end to end thereof, or thereabout, and the other limb is projected through one of the end pieces 3 and extends into the casing, and is embedded in the material therein, thereby to hold it in place.

The novelty as an entirety is designed primarily to be utilized as emblematic of the Yule-log, and is, of course, placed in an open fire-place and ignited, whereupon it burns until completely destroyed as would an original log. It is apparent that a great variety of effects may be produced by the use of different material within the log and while I particularly contemplate the use and treatment of such materials as will most nearly simulate the combustion and effect of a natural log, it is to be understood that I in no wise limit myself specifically thereto.

In lieu of the form of case illustrated in Figs. 1 to 7, other forms may be adopted, emblematic of the different holidays of the year, as for instance, in Fig. 8 a heart-shaped case is shown, and the sparkler is represented as an arrow which is extended through the case, emblematic of Valentine's day; in Fig. 9 a cylindrical case is shown and the sparkler is represented as a hatchet, emblematic of Washington's birthday; in Fig. 10 a cylindrical case representing a fire-cracker is shown, and the sparkler projecting from one end of it; in Fig. 11 a case representing a torpedo is shown having a sparkler projecting from it, both the forms shown in Figs. 10 and 11 being emblematic of the Fourth of July; in Fig. 12 a case representing a pumpkin is shown, the sparkler projecting from it as a stem, being emblematic of Halloween; in Fig. 13 a case representing a plum-pudding with a sparkler projecting from it as a stem, is shown, emblematic of Thanksgiving; in Fig. 14 a case representing a flower-pot is shown having a sparkler extended from it in the form of the stem of a flower, being emblematic of Easter.

50 I claim:

1. A pyrotechnic novelty comprising a combustible casing simulating a log, foraminous ends for the casing, a combustible material filling for the casing, and an ignition

65 fuse leading from said material to a point 55 beyond the casing and terminating in a "sparkler" length.

2. A pyrotechnic novelty comprising a combustible casing simulating an article associated with a festival occasion, a material filling composed in part of divided cork, chips of wood, and wood fiber, portions of any one of said materials being chemically treated to produce distinctive pyrotechnic effects during combustion.

3. A pyrotechnic novelty comprising a paper casing, distending rings within the ends of said casing, foraminous ends secured to the casing, a combustible filling within the casing arranged to present a varied pyrotechnic effect during combustion, a fuse leading from the material to and beyond the casing for initial ignition, all the parts described being completely destroyed in the operative use of the novelty.

4. A pyrotechnic novelty comprising a paper casing, distending rings within the ends of said casing, foraminous ends secured to the casing, a combustible filling within the casing arranged to present a varied pyrotechnic effect during combustion, a fuse leading from the material to and beyond the casing for initial ignition, all the parts being impregnated with a chemical for producing combustion of such materials.

5. The pyrotechnic novelty herein described consisting of a cylindrical paper casing, substantially thick rings at the ends thereof, foraminous ends secured to the casing, a combustible filling arranged within the casing and treated chemically for varied pyrotechnic effects while burning, a wad of cotton fiber arranged within the casing and extended through an opening in the side thereof, all of said parts being impregnated with paraffin, and an igniting device consisting of a wire having igniting material arranged thereon in juxtaposition to the wad of cotton fiber, said wire being attached to the casing.

In testimony whereof, I have signed my name to this specification, in the presence of two subscribing witnesses.

ELIZABETH T. HINCKS.
